UNITED STATES PATENT OFFICE.

HARRY T. SHEARER, OF WAYNESBORO, PENNSYLVANIA, ASSIGNEE TO LANDER CO., COMPANY, OF WAYNESBORO, PENNSYLVANIA, A CORPORATION.

WORK-REST FOR GRINDING-MACHINES.

1,078,561.

Specification of Letters Patent.

Patented Nov. 11, 1913.

Application filed August 8, 1911, Serial No. 643,935. Renewed September 23, 1913. Serial No. 755,422.

To all whom it may concern:

Be it known that I, HARRY T. SHEARER, a citizen of the United States, residing at Waynesboro, in the county of Franklin and State of Pennsylvania, have invented certain new and useful Improvements in Work-Rests for Grinding-Machines; of which the following is a specification.

My said invention consists in certain improvements in the details of construction of work-rests for grinding machines, whereby the rest may be adjusted to serve as a gage to substantially determine the size of the work, all as will be hereinafter more fully described and claimed.

Referring to the accompanying drawings which are made a part hereof and on which similar reference characters indicate similar parts, Figure 1 represents a view partly in section and partly in side elevation of one of my improved work-rests, Fig. 2, a detail top plan of the left end of Fig. 2, with a portion of the part C broken away, and Fig. 3, a detail rear elevation of the screw rod 25 and the arm 28 thereon, and the adjacent parts.

In said drawings the portions marked A represent the work-table, B the frame of the work-rest and C the slider carrying the horizontal rest-block.

In the main, the work-rest illustrated is of a form in common use and the structure will be described only briefly except as to those parts to which my invention especially relates.

The frame B is mounted on the table A by means of a clamping screw, or pin, a, in the usual manner. The sliding part C is mounted in slides b and the top of the frame B and may be clamped in any position desired by means of the clamping screw C', in the usual manner. A cylindrical part c is mounted to slide in a corresponding bore in part C and carries the bearing block c', preferably of wood, on its outer end, held in place by a clamping screw c''. In the outer end of the part C is mounted adjusting sleeve 10, being exteriorly screw-threaded into a screw-threaded perforation leading into the bore in which cylindrical part c is mounted. A jam-nut 11 serves to hold said sleeve 10 in adjusted position. A screw-threaded rod 12 is mounted in said sleeve 10 formed with a screw-threaded section adapted to engage 55 with interior screw-threads at the inner end

of sleeve 10. A spring 13 is interposed between the inner end of the bore in part C and the adjacent end of an aperture in part c which normally presses the bearing block c' against the work. A transversely projecting arm 14 is clamped to rod 12 adjacent to the end of sleeve 10 by means of a screw 15. A pin 16 is mounted in a recess in an adjacent part of the slider C with its end projecting into the normal path of said arm 14 when turned to a predetermined position. A spring 17 normally holds said pin outward and a transverse pin 18 is adapted to slide in a slot to limit the outward movement of said pin. Said slot is formed at its inner end with an angular off-set e in which pin 16 may engage and pin 18 be held with its end within the aperture in which it is mounted, when desired, as when this improvement is not desired or when the arm 14 has not yet been adjusted to the desired position.

The vertical support comprises an arm 20 mounted on a pivot 21 carrying the bearing block 22 on its outer end secured thereto by a clamping screw 23 and adapted to bear against the underside of the work W. Said pivoted arm 20 has a depending portion 24 with which a screw-rod 25 is adapted to engage. Said screw-rod is mounted in a screw-threaded perforation in base B and has a collar 27 threaded thereon between which and the base of an aperture at the outer end of said screw-threaded part is mounted a spring 26 by means of which said screw-rod 25 is kept under a tension in its threaded seat in the base B. An arm 28 is clamped to rod 25 by a screw 29 in the same manner as described for arm 14. Said arm 28 is adapted to strike a projecting pin 30 mounted in the adjacent part of base B in the same manner as described for pin 16.

In operation, the grinding of the first piece of work proceeds and the screws 12 and 25 are kept adjusted to hold the bearing block c' and 22 against the respective sides of the work W. When the work has been ground to the desired size, pins 16 and 30 being projected beyond the faces of their respective seats, the arms 14 and 28 are adjusted so that their top faces will strike and bear against the undersides of said pins. When the next piece of work is put into the machine to be ground the pins 12 and 25 are backed in their seats to bring the bearing

blocks 21 and 22 of the work-rest into proper position to steady the work and the work proceeds as before, the operator turning screws 12 and 25 inward until the arms 14 and 22 strike pins 16 and 30, respectively, which indicates that the work has been ground to a size corresponding with the first piece of work.

Having thus fully described my said invention, what I claim as new and desire to secure by Letters Patent, is:

1. A work-rest for grinding machines comprising blocks mounted on movable supports, said movable supports, screw-rods for adjusting said movable supports to keep said blocks in contact with the work, an adjustable transverse arm on said screw-rods, and a strike located adjacent and in the path of said arm to limit the forward adjustment of said screw-rods at a predetermined point, substantially as set forth.

2. A work-rest for grinding machines comprising a frame, movable supports carrying bearing blocks adapted to bear against the sides of the work opposite the thrust of the grinding wheel, screw-rods for operating said movable supports, a transverse arm mounted on each of said screw-rods, means for adjusting each transverse arm, a strike located in an adjacent part alongside each of said screw-rods and adapted to contact with its arm and limit the movement of the rod at a predetermined point, substantially as set forth.

3. A work-rest for grinding machines comprising a base, movable parts carrying bearing blocks mounted on said base, screw-rods for adjusting said movable parts to carry the bearing blocks in relation to the work, and means for limiting the forward adjustment of said screw-rods at a predetermined point, substantially as set forth.

4. A work-rest for grinding machines comprising a base, movable parts carrying bearing blocks adapted to bear against the sides of the work, screw-rods for operating said movable parts, transverse arms adjustably mounted on said screw-rods, strikes located normally in the path of said arms, and means for holding said strikes out of the path of said arms, substantially as set forth.

5. A work-rest for grinding machines comprising a base, movable supports for the bearing blocks, said bearing blocks mounted on said movable supports, horizontally adjustable rods for operating said movable supports, and means for limiting the forward movement of said rods at a predetermined point, substantially as set forth.

In witness whereof, I, have hereunto set my hand and seal at Waynesboro, Pennsylvania, this 28th day of July, A. D. nineteen hundred and eleven.

HARRY T. SHEARER. [L. s.]
